LEATHER TEMPERING BOX

Filed Sept. 13, 1927

UNITED STATES PATENT OFFICE

PRESLEY V. CLACK, OF KNOXVILLE, TENNESSEE

LEATHER-TEMPERING BOX

Application filed September 13, 1927. Serial No. 219,343.

This invention relates to tempering devices and while capable of general use is more particularly adapted for tempering leather or pieces thereof, and also for tempering 5 blanks of leather in the form of half or whole soles that are employed in the making or repairing of shoes.

It has heretofore been proposed to temper leather in the form of strips or cut soles, by 10 dipping the same in water, but this method of tempering shoe soles has certain defects and disadvantages in that, owing to the various thicknesses of leather employed in the trade, the matter of tempering the same by dipping 15 the leather in water results, on the one hand, in an uneven tempering of the leather and, on the other hand, in the production of what is known as "water hard" leather caused by over-saturation and hardening of the leather, especially when the same is not used immediately after tempering. In the case of "water 20 hard" leather, the same becomes brittle and unworkable and cannot be retempered with out the expenditure of considerable time.

25 Consequently, when "water hard" leather is used in the making or repairing of shoes, the result is an inferior product by reason of the fact that the fibers of the leather break so that the length of the life of the shoe is materially decreased. Where shoes are repaired 30 with "water hard" leather, such leather cannot be conformed to the inner sole of the shoe, but on the contrary the inner sole has to be drawn down to the "water hard" leather 35 with the result that the upper of the shoe is pulled out of shape and produces discomfort to the wearer.

One object of the present invention is to 40 provide a box or container wherein the pieces of leather may be placed in proximity to a body of liquid, so that the leather pieces will be evenly tempered throughout.

Another object of the invention is to provide 45 a shoe sole tempering box, with a rack or support that holds the soles or blanks of leather on edge in proximity to each other, so that moisture may pass through and between the soles or blanks to thoroughly and evenly temper the same.

50 A further object of the invention is to pro-

vide a tempering box for leather blanks or the like, with means such as a heating unit for maintaining the body of water in the box at an even or approximately constant temperature throughout the leather tempering operation. 55

Another object of the invention is to provide a tempering box for leather, with ventilating means so arranged as to prevent discoloration of the leather being tempered in the box. 60

Other objects of the invention will appear as the description thereof proceeds.

In order to more clearly understand the invention, reference may be had to the accompanying drawings which show one embodiment of the inventive idea and wherein— 65

Fig. 1 is a view in perspective of a box embodying the invention;

Fig. 2 is a cross section on the line 2—2 of Fig. 1; and

Fig. 3 is a perspective view of the rack or tray for supporting the leather strips.

Referring to the drawings, wherein like reference characters designate like parts throughout the several views, 5 indicates a box or container, preferably made of sheet metal or the like, and having side walls 6, 6, end walls 7, 7 and a top 9. The box is divided into two compartments 10 and 11, by a partition 8 that is secured to the side and end walls of the box in any suitable manner so that the compartment 11 is approximately one-third the size of the compartment 10. The compartment 11 is adapted to receive a heating unit 12, hereshown as an electrical heater, provided with connecting plug 12', which is secured to the walls of the box in a suitable manner. Air vents for the compartment 11 may be provided in the side or end walls 6, 6 and 7, 7, respectively. Access to the interior of the compartment 11 for installing or inspecting the heating unit therein, is preferably had through an opening 14 formed in one of the end walls of the box and normally closed by a cover 15 that is hinged at 16, 16 to the box. 75 80 85 90 95

The compartment 10 is adapted to hold a body of water supplied therein through a pipe 17 communicating with said compart- 100

ment and having a cap or closure 18 threaded therein to normally close the pipe to the atmosphere. The body of water preferably has a height of approximately five inches, although it is to be expressly understood that the height of the water in the compartment 10 may be varied as desired in accordance with the particular conditions under which the tempering is carried on and in accordance with the particular construction of the tempering box. Secured on the inner surfaces of the walls of the box and preferably located in the corners thereof, are brackets 19, 19 the upper or supporting surfaces of which are preferably located at a height of approximately one inch above the level of the water in the box. These brackets are adapted to support a rack or holder 20 for pieces of leather, shoe sole blanks in the form of half or whole soles, or other types of blanks employed in the making of or repairing of shoes. The rack 20 preferably has a foraminous bottom made of wires 21 and 22 that are crossed over each other respectively to form an open mesh bottom for the rack which, when the rack is in position on the brackets 19, is disposed at a height of approximately one inch above the level of the body of water in the box. The rack bottom 21, 22 may be in the form of a continuous wire providing the open mesh construction referred to, or wires 21, 22 forming the bottom of the rack may be separate strips of wire soldered or otherwise suitably secured to the sides 23, 23 and end 24, 24 of the rack, respectively. The rack 20 may be divided into compartments, if desired, and these compartments, for example, may be of varying dimensions to accommodate pieces or blanks of leather varying in length with respect to each other. As herein shown, the rack 20 is divided into three compartments 25, 26 and 27 by a partition 28 that extends longitudinally of the rack intermediate the side walls thereof, and a partition 29 that extends at right angles to the partition 28. The compartments 26 and 27, clearly shown in the drawing, vary in size with respect to each other and also with respect to the compartment 25.

In the use of the device strips of leather or cut soles, or the like, are placed on edge in the rack 20 so as to rest on the bottom 21, 22 thereof in a substantially vertical position. When strips of leather are to be tempered, a plurality of the same are placed as described with their faces opposing each other so that moisture from the body of water in the box may pass upwardly between the strips and thoroughly penetrate each strip supported edgewise on the bottom of the rack. When the cut soles (either half or whole soles) are to be tempered, they are likewise placed on edge on the bottom of the rack,

said soles preferably being arranged in pairs and being placed in the compartments of the rack according to the size of the soles that are to be tempered.

In order to support the strips of leather for the cut soles, on edge as above described, the top of the rack is provided with holding wires 30 that extend in spaced relation across the top of the rack, and engage the opposite sides of packs of leather strips or cut soles, to hold the latter on edge as above described. 70 75

The rack 20 is preferably provided with handles 31, 31 at the ends thereof, for conveniently placing the rack in or removing the same from the tempering box. 80

In order to insure an even temperature of the body of water in the box, an opening 32 is formed in one of the walls of the box below the level of the body of water, through which opening water may pass into a cup 33 secured on the outer surface of the box in any suitable manner. A thermometer 34 has a bulb 35 which is disposed within the cup 33 to indicate the temperature of the water in the box, so that the heating unit may be controlled to maintain the temperature of the body of water approximately constant throughout the tempering operation. This thermometer is preferably secured to the box by a perforated guard 35' clamped or riveted to the box or otherwise suitably fastened thereto, as desired. 90 95

The top 9 of the box is preferably hinged thereto at 36, 36 and is provided with means for ventilating the box so as to insure against 100 discoloration of the leather being tempered in the box. For this purpose, uniformly distributed ventilating openings 37 are provided in the top of the box throughout the surface thereof so that discoloration of the leather being tempered is absolutely prevented. While the distance between the openings 37 may vary in accordance with atmospheric 105 conditions or other conditions under which the tempering operation is carried on, I have found by experiment that if the openings are formed throughout the surface of the top of the box and disposed at approximately one inch from each other that discoloration of the leather being tempered is absolutely prevent- 110 ed. 115

Operation.—In the operation of the device, the compartment 10 is filled with water to a height slightly below the leather supporting rack 20. I have found one inch below to be 120 satisfactory. The strips of leather, cut soles, or the like, are then placed on edge on the rack 20 and the cover 9 is closed. I have found that with the height of the body of water being approximately five inches; with the level of the water one inch below the lower edges of the strips of leather, or cut soles; and with the ventilating openings 37 spaced approximately one inch apart; that the leather can be tempered evenly in approximately 130

twelve hours, with the temperature of the body of water maintained at substantially 78° or 79°. If, on observation of the thermometer, the temperature of the water is below, say 79°, the heater is turned on until the temperature of the water is brought up to the desired temperature and then turned off. By observing the thermometer and turning the heater on and off as necessary, the temperature of the body of water in the box may be maintained substantially constant with the result that the leather in the box will be tempered in approximately twelve hours. After the leather is tempered, the same may be used as desired from the box, and maintained in tempered condition while in the box by maintaining the body of water at the temperature substantially as above indicated.

I do not desire to be understood as limiting myself to the exact details of construction and arrangement as herein described and illustrated, as it is manifest that variations and modifications may be made without departing from the spirit and scope of my invention and the terms of the following claims, hence I wish it to be understood that I reserve the right to make any such changes, or modifications as may fairly fall within the scope of the appended claims when fairly construed.

What is claimed is:

1. In a leather-tempering box, the combination of a liquid-containing tank, a rack having a foraminous bottom supported above the surface of the liquid, said rack having means for holding leather strips in a substantially vertical position, means for regulating the temperature of the liquid in the tank, and ventilation means above the rack.
2. In a leather-tempering box, the combination of a liquid-containing tank, means for supplying liquid to the tank, means for withdrawing the liquid therefrom, means regulating the temperature of said liquid, means for supporting leather strips on edge above the liquid in the tank and in open communication therewith, and means for ventilating the box above the rack.

In testimony whereof I have signed this specification.

PRESLEY V. CLACK.
